United States Patent Office

Des. 230,403
Patented Feb. 19, 1974

230,403

HAND HELD DATA READER OR SIMILAR ARTICLE

Gosta Roland Englund, Stockholm, Sweden, assignor to
Svenska Dataregister AB, Solna, Sweden

Filed July 6, 1971, Ser. No. 160,250

Term of patent 14 years

Int. Cl. D14—02

U.S. Cl. D26—5 C

FIG. 1

FIG. 2

FIG. 3

FIG. 4

FIG. 5

FIG. 6

FIG. 7

FIG. 8

FIG. 9

FIG. 10

FIG.11

FIG.12

FIG. 1 is a perspective view of a hand held data reader or similar article embodying my invention;

FIG. 2 is an elevational view thereof;

FIG. 3 is a top plan view thereof;

FIG. 4 is a bottom plan thereof;

FIG. 5 is a perspective view of a modified form of the hand held data reader or similar article shown in FIG. 1;

FIG. 6 is an elevational view;

FIG. 7 is a top plan view;

FIG. 8 is a bottom plan view;

FIG. 9 is a perspective view of a second modified form of the hand held data reader or similar article shown in FIG. 1;

FIG. 10 is an elevational view thereof;

FIG. 11 is a top plan view thereof; and

FIG. 12 is a bottom plan view thereof.

I claim:

The ornamental design for a hand held data reader or similar article, as shown and described.
